DEVICE FOR FIRING CANNONS

Filed Jan. 22, 1926

UNITED STATES PATENT OFFICE.

EDUARDO BUSTAMANTE, OF STATEN ISLAND, NEW YORK.

DEVICE FOR FIRING CANNONS.

Application filed January 22, 1926. Serial No. 83,016.

This invention relates generally to cannons and the like, the invention having more particular reference to a novel device for firing cannons and the like. The invention 5 has for an object the provision of an improved firing device which is noiseless in operation.

For further comprehension of the invention, and of the objects and advantages 10 thereof, reference will be had to the following description and accompanying drawing, and to the appended claims in which the various novel features of the invention are more particularly set forth.

15 Fig. 1 of the drawing is a side elevational view of my improved device as applied to a cannon, showing certain parts in section.

Fig. 2 is section of the valve chamber, taken on the line 2—2 of Fig. 1.

20 Fig. 3 is a section of the contact box, taken on the line 3—3 of Fig. 1.

As here embodied my improved firing device as applied to the cannon 10, of any conventional design and construction as 25 ordinarily used, comprises an oxygen tank 11 and a hydrogen tank 12 having shut off valves 13 and valve bodies 17 with gages 14 to record the rate of flow, when the valve 13 is open, and pressure gages 15 to record 30 the pressure of the hydrogen or oxygen in the tanks 11 and 12, supplementary gages 16 being provided as a means of regulating the rate of flow of hydrogen or oxygen, the above mentioned device being as ordinarily 35 used for this purpose. The valve bodies 17 being connected by means of pipes 18 and 19, having shut off valves 20 and 21 respectively to low pressure tanks 22 and 23 respectively, having pressure gages 24 and 25, 40 and safety valves 26 and 27, respectively, the low pressure tanks 22 and 23 being connected to a main line 28 having shut off valves 29 by means of pipes 30 and 31 or any suitable 45 means, respectively, the said main line 28 leading to a valve chamber 32, of any suitable design and construction, and having a pressure gage 33.

To accommodate a circular or disc valve 34 held on its seat 35 by means of a compression spring 36 and having an aperture 37 to register with the aperture 38, when the disc valve 34 is rotated by means of a suitable located shaft 39 rotatively mounted in a frame 40 and having suitably attached 55 thereto a bevel gear 41 meshing with a suit-

able bevel gear 42 attached to a main shaft 43 rotatively mounted in the frame 40, and having attached thereto a suitable bevel gear 44 meshing with the bevel gear 45 attached to the shaft 46 rotatively mounted in the frame 40, and having attached thereto a bevel gear 47 meshing with a suitable bevel gear 48 attached to a shaft 49 rotatively mounted in suitable bearings 50 and having attached thereto a pulley 51 and a belt 52 60 extended over the pulley 51 and the pulley 53 attached to the motor shaft 54 of the motor 55 suitably connected to any convenient source of power, not shown on the accompanying drawing, the heretobefore construction being such as will permit the motor 55 to rotate or revolve the disc valve 34 and the ring gear 56 by means of a suitable pinion 57, meshing with the ring gear 56, and attached to the main shaft 43, the 65 said ring gear 56, being rotatively attached to the breech of the cannon 10 and held in position by means of a flange 58, and having apertures 59 to register with the apertures 60 when the ring gear 56 is rotated. The 70 pinion 61, is conveniently attached to the main shaft 43, and meshes with a suitable bevel gear 62 attached to the shaft 63 rotatively mounted in the frame 40, and having suitably attached thereto a contact arm 64, 75 and having connected thereto, one extremity 65 of a suitable inductance coil 66 by means of a suitable terminal 66' and a protruding portion 67, the said contact arm 64 making contact with the terminal 68 when rotated 80 by means of the heretobefore mentioned shaft 63 and bevel gear 62. The terminal 85 being connected by means of a suitable wire 69 to a spark plug 70 of the conventional design. The inductance coil 66 being also 90 suitably connected to a switch 71 and a battery 72, in any other suitable source of current. The aperture 38 being connected to a 95 valve housing 75, by means of a pipe 73 or any other suitable means, containing a valve 100 76 held in a closed position by means of a suitable spring 74.

It is obvious that I have provided a means of supplying a mixture of oxygen and hydrogen to a cannon, and that I have also 105 provided a means of firing same by means of a spark, it is furthermore, obvious, that I have provided a means of opening apertures in the breech of a gun so as to permit a current of air through the barrel of the said 110

cannon; it is further obvious that I have also provided a means of timing the above mentioned operations, as may be required.

While I have above described the preferred form, construction, and arrangement of the several elements employed, it will be understood that the device is, nevertheless, susceptible of considerable modification therein, and I therefore reserve the privilege 10 of resorting to all such changes as may be fairly embodied within the spirit and scope of the invention as claimed.

Having thus described my invention, what I claim as new and desire to protect by Letters Patent of the United States is as follows:—

1. A firing device for cannons and the like comprising tanks, connected to the cannon a disc valve and a contact arm and a 20 means of rotating said disc valve and said contact arm so as to fire the said cannon said tanks connected to low pressure tanks and to the disc valve chamber.

2. A firing device for cannons and the like comprising tanks connected to low pressure tanks and to a disc valve, having an aperture a means of rotating the said disc valve, an aperture so located as to register with the said aperture as a means of distributing the contents of the said tanks to a cannon through a valve, a means of rotating a contact arm so as to fire the said cannon by means of a spark plug, a coil and a battery, a means of opening apertures in the 35 said cannon by a ring gear operatively attached to the said mechanism.

3. A firing device for cannons and the

like comprising tanks connected to low pressure tanks and to a valve chamber containing a disc valve having an aperture, a means of 40 rotating the said disc valve by gears and shafts, an aperture so located as to register with the said aperture as a means of distributing the contents of the said tanks to a valve housing containing a valve, and to the 45 said cannon, a means of rotating a contact arm by gears and shafts rotatively driven by the heretobefore said gears and shafts, so as to fire the said cannon by means of completing the circuit to a spark plug in 50 the said cannon, and to a coil and a battery.

4. A firing device for cannons and the like comprising tanks connected to low pressure tanks and to a valve chamber containing a disc valve having an aperture, a means of 55 rotating the said disc valve by gears and shafts, an aperture so located as to register with the said aperture as a means of distributing the contents of the said tanks to a valve housing containing a valve, and to the 60 said cannon, a means of rotating a contact arm by gears and shafts rotatively driven by the heretobefore said gears and shafts, so as to fire the said cannon by means of completing the circuit to a spark plug in 65 the said cannon, and to a coil and a battery, and a means of opening apertures in the said cannon by a ring gear rotatively driven by a pinion attached to a shaft comprising one of the heretobefore said shafts.

In testimony whereof I have affixed my signature.

EDUARDO BUSTAMANTE.
